UNITED STATES PATENT OFFICE.

LUTHER A. YEISER, OF PHILADELPHIA, PENNSYLVANIA.

GARMENT-HOOK.

No. 856,830.

Specification of Letters Patent.

Patented June 11, 1907.

Application filed September 5, 1905. Serial No. 277,084.

To all whom it may concern:

Be it known that I, LUTHER A. YEISER, a citizen of the United States, residing in Philadelphia, Pennsylvania, have invented 5 certain Improvements in Garment-Hooks, of which the following is a specification.

This invention consists of an improved hook particularly designed for use on garments; one object of the invention being to 10 provide a hook of such construction that its thread holding eyelets cannot be pulled apart or caused to overlap each other.

Another object of the invention is to so arrange the wire forming the garment hook 15 that an auxiliary thread holding eyelet is provided and that at such a place upon said hook as will permit its being sewn to a garment and held at three points in such manner as will firmly and immovably retain the 20 hook as a whole in a given position.

These objects I attain as hereinafter set forth, reference being had to the accompanying drawings, in which:—

Figure 1, is a plan view of one form of my 25 improved hook; Fig. 2, is a side elevation of the hook shown in Fig. 1; Fig. 3, is a horizontal section of the hook shown in Fig. 2, the same being taken on the line 3—3 of said figure; Fig. 4, is a vertical section of the hook 30 shown in Fig. 2, taken on the line 4—4 of said figure; Fig. 5, is a plan view of a form of my improved hook with the auxiliary thread holding eyelet omitted; Fig. 6, is a side elevation of the structure shown in Fig. 5; Fig. 7, is a horizontal section of the hook shown in 35 Fig. 6, the same being taken on the line 7—7 of said figure, and Fig. 8, is a vertical section taken on the line 8—8, Fig. 6.

Referring to Figs. 1 to 4 of the above 40 drawings, it will be seen that my improved hook consists of a single wire bent to form two thread holding eyelets A and A' tied together, with an auxiliary thread holding eyelet C at the end of the hook opposite that 45 having the eyelets A and A'. It will be seen that, starting at the thread holding eyelet A, the wire of the hook runs from this toward the rear of the bill B and is then bent upwardly, extended forwardly and then rearwardly to form the bill. From the rear of 50 the bill it extends downwardly and forwardly to form the second thread holding eyelet A', from which it extends between the side members a and a' of the bottom of the hook to the rear thereof and is then bent up-

wardly and out as shown in Fig. 3; being finally curved into the eyelet C and having its end c held in engagement with the interior of the back part of the hook. This auxiliary eyelet C is preferably made to lie in substantially the same plane as that of the eyelets A and A' and, in addition to providing an extra or third eyelet serves to stiffen the hook as well as to prevent the accidental springing of the catch or hump a⁴ with consequent release of the eye.

In order to prevent the possibility of the eyelets A and A' being pulled apart or caused to overlap one another the end a² of the wire is extended from the eyelet A over the section of wire a and the intermediate section a³, and is finally bent downward within the rear of the eyelet A' so as to lock or tie together said two eyelets. It will be noted, moreover, that by so placing this end a² of 75 the wire, the space at the rear of the eyelet A', through which the holding threads for the hook have been frequently found to escape, is completely filled. The intermediate section a³ of the wire extending along the 80 base of the hook is provided with a curved hump or holding portion a⁴.

In Figs. 5 to 8 inclusive, I have shown a form of hook in which the auxiliary eyelet C is omitted and the intermediate wire a³ extended between the two wires forming the bill, it being curved downwardly and forming a second hump a⁵. In any case, I preferably tie the two eyelets A and A' together by means of the end a² of the wire. In Figs. 90 5 and 6 I have shown a form of eye D particularly designed for use with hooks of the class to which my invention belongs, this eye having two thread holding eyelets E and E' and a hook-engaging loop projecting in a plane 95 inclined at a relatively acute angle to the plane of said eyelets.

From the above it will be seen that it is a practical impossibility to separate the two thread holding eyelets A and A' of a hook 100 made according to my invention, while such a hook may, if desired, be held at three points to its supporting fabric by means of properly placed stitches in the eyelets A, A' and C.

I claim

1. A garment hook having a base portion 105 formed by three substantially parallel sections of the same wire, certain portions of said wire being bent to form thread eyelets and one of its ends being engaged with a pli-

105

110

rality of said parallel sections to prevent separation of the same, substantially as described.

2. A garment hook made of a single piece 5 of wire having two adjacent thread eyelets and three substantially parallel portions extending therefrom, the end of the wire forming one of the eyelets being extended around two of said parallel portions so as to prevent 10 separation of said eyelets, substantially as described.

3. A garment hook having a base portion formed by three substantially parallel sections of the same wire, certain portions of 15 said wire being bent to form thread eyelets, and one of its ends being engaged with a plurality of said parallel sections to prevent separation of the same, a portion of the wire comprising the hook being bent to form a 20 hump, substantially as described.

4. A garment hook consisting of a piece 25 of wire bent to form a thread holding eyelet, said wire being extended from said eyelet and then curved upwardly and forwardly and again to the rear to form a bill, being then extended 30 from the rear of said bill downwardly and forwardly, then curved to form a second thread holding eyelet, and being finally extended rearwardly intermediate its other 35 two sections, the first end of said wire being engaged with said intermediate extending portion, and one of the sections parallel therewith, to lock together said parts, substantially as described.

5. A garment hook consisting of a piece of 40 wire bent to form a thread holding eyelet, said wire being extended from said eyelet and then curved upwardly and forwardly and again to the rear to form a bill, extended 45 from the rear of said bill downwardly and forwardly, being then curved to form a second thread holding eyelet and extended rearwardly intermediate its two side sections, said intermediate section being curved outwardly between one side section and the bill, and then bent around the rear of the hook to 50 a position between the other side section and the bill to form an auxiliary thread holding eyelet, with means for locking together the two thread holding eyelets, substantially as described.

6. A garment hook consisting of a piece of 55 wire bent to form a thread holding eyelet, said wire being extended from said eyelet and then curved upwardly and forwardly and again to the rear to form a bill, being then ex-

tended from the rear of said bill downwardly and forwardly, then curved to form a second thread holding eyelet, and being finally extended rearwardly intermediate its other two 60 sections, the first end of said wire being caused to tie together parts of the two thread holding eyelets, substantially as described.

7. A garment hook consisting of a piece of wire bent to form a thread holding eyelet, 65 said wire being extended from said eyelet and then curved upwardly and forwardly and again to the rear to form a bill, extended from the rear of said bill downwardly and forwardly, being then curved to form a second 70 thread holding eyelet and extended rearwardly intermediate its two side sections, said intermediate section being curved outwardly between one side section and the bill, and then bent around the rear of the hook to 75 a position between the other side section and the bill to form an auxiliary thread holding eyelet, with means for locking together the two thread holding eyelets, substantially as described.

8. A garment hook consisting of a piece of wire bent to form a thread holding eyelet, 80 said wire being extended from said eyelet and then curved upwardly and forwardly and again to the rear to form a bill, extended 85 from the rear of said bill downwardly and forwardly, being then curved to form a second thread holding eyelet and extended rearwardly intermediate its two side sections, said intermediate section being curved outwardly between one side section and the bill, and then bent around the rear of the hook to 90 a position between the other side section and the bill to form an auxiliary thread holding eyelet, substantially as described.

9. A garment hook constructed of a single 95 piece of wire bent to form a shank having at one end attaching eyes and at its opposite end a bill, an integral spring tongue having therein an offset forming a detent, and an attaching eye formed on the end of said tongue, 100 said eye being bent around and encircling the bill of the hook, the end of the eye terminating between the bill and the shank of the hook, substantially as described.

In testimony whereof, I have signed my name to this specification, in the presence of two subscribing witnesses.

LUTHER A. YEISER.
